Primary Examiner — Cary M Robinson*Assistant Examiner* — Adam C Mager(74) *Attorney, Agent, or Firm* — ScienBiziP, P.C.(57) **CLAIM**

The ornamental design for a license plate frame, as shown and described.

DESCRIPTION

FIG. 1 is a front, right, and top perspective view of a license plate frame, showing my new design;

FIG. 2 is a rear, left, and bottom perspective view thereof;

FIG. 3 is a front, right, and top perspective view of the license plate frame shown in one state of use;

FIG. 4 is another front, right, and top perspective view of the license plate frame shown in another state of use;

FIG. 5 is a front elevation view thereof;

FIG. 6 is a rear view thereof;

FIG. 7 is a left side elevation view thereof;

FIG. 8 is a right side elevation view thereof;

FIG. 9 is a top plan view thereof;

FIG. 10 is a bottom plan view thereof; and,

FIG. 11 is an enlarged view of an encircled area labeled "11" in FIG. 7.

The broken lines shown in the drawings are included for the purpose of illustrating portions of the license plate frame that form no part of the claimed design.

Dot-dash broken lines in FIGS. 7 and 11 framing portions of the claimed design that are illustrated for enlargements form no part of the claimed design.
